TOBACCO PIPE

Albert E. Dietz, Washington, D. C., assignor of
one-half to Edward J. Biggins, Washington,
D. C.

Application October 19, 1944, Serial No. 559,401

3 Claims. (Cl. 131—179)

1

This invention relates to an improved tobacco pipe.

An object of the invention is to provide a pipe embodying a foraminous barrel and surrounding cage within the bowl, the cage being provided with a cap to normally overlie the barrel, wherein, if so desired, the barrel may be filled with tobacco and smoke drawn therefrom through the stem of the pipe, or wherein, if preferred, the barrel may be removed and the cage employed to hold the tobacco to be smoked, and wherein, if so desired, the barrel and cage may both be removed, when the bowl may be filled with tobacco and the pipe used in the usual manner.

A further object of the invention is to provide a pipe embodying a wrapper holder in conjunction with the barrel, wherein a conventional cigarette paper may be wound about the holder and sealed by moisture to form a cylindrical wrapper, when the holder with the wrapper thereon may be installed in the barrel, wherein the wrapper may then be filled with tobacco to form a cigarette, and wherein the pipe may then be used without the bowl but with the cage, or without both the bowl and cage, as a holder for the cigarette.

And a still further object of the invention is to provide a pipe wherein the tobacco either in the cage or in the barrel may be lighted without opening the cap.

Other and incidental objects of the invention will appear during the course of the following description, and in the drawings:

Figure 1 is a side elevation of my improved pipe.

Figure 2 is a plan view of the pipe.

Figure 3 is a vertical section on the line 3—3 of Figure 1.

Figure 4 is a vertical section showing the pipe used, without the bowl, as a cigarette holder.

Figure 5 is a vertical section showing the pipe used, without the bowl and cage, as a cigarette holder, the barrel being shown in elevation.

Figure 6 is a perspective view showing the wrapper holder in detail.

Figure 7 is a detail perspective view showing the manner in which a cigarette paper is wound about the wrapper holder to form a wrapper.

Figure 8 is a perspective view showing the barrel in detail.

In carrying the invention into effect, I employ a base 10 having a series of stepped, circular seats comprising a seat 11 surrounded by spaced, upstanding spring tongues 12, a somewhat lower seat 13 surrounded by spaced, upstanding spring tongues 14 somewhat longer than the tongues 12, and a still lower seat 15 which is without sur-

2

rounding tongues. The base 10 may be of plastic or other approved material and the spring tongues 12 and 14 may be integral with the base, as shown, or attached thereto in any suitable manner.

Centrally of the seat 15, the base 10 is provided with a passage 16 in which is fixed a sleeve 17, and communicating with said passage is a duct 18 closed at its forward end by a removable plug 19, while a suitable stem 20 is detachably engaged 10 with the base at the rear end of said duct. The stem 20 may be either straight, as shown, or suitably curved like various conventional stems and, as will be observed, the plug 19 may be removed when an appropriate cleaner may be introduced 15 through the duct and stem for cleaning both.

Removably engaged in the seat 11 of the base 10 is a bowl 21 frictionally held in position by the spring tongues 12. This bowl may be of any approved material and is provided at its upper 20 end, as seen in Figures 1 and 2 of the drawings, with a notch 22.

Removably engaged in the seat 13 of the base 10 is a cylindrical, foraminous cage 23 frictionally held in position by the spring tongues 14, 25 the cage being of woven wire or any approved material bent into cylindrical shape and soldered at its meeting edges. This cage is provided at its ends with metallic reinforcing bands 24 soldered to the wire of the cage, and mounted upon the 30 upper end of the cage is a cap 25 connected with the cage by a suitable hinge 26 which, as best brought out in Figure 1, is received within the notch 22 of the bowl 21 so that the cap may swing open. The cap may be of metal or other approved 35 material. A conventional hinge is shown, comprising mating parts on the cap and the uppermost of the bands 24, and a pintle connecting the parts.

It is now to be observed that the cap 25 is 40 formed with a cylindrical body-wall 27 which, when the cap is closed, freely fits within the bowl 21 and, at its lower margin, is bent into U-shape to provide an inner ring 28 which terminates in an inwardly overhanging flange 29. As will be 45 noted, the ring 28 freely fits about the upper end of the cage 23 when the cap is closed while the flange 29 abuts the upper end edge of the cage for limiting the cap in closed position.

Spun from the upper end portion of the wall 50 27 of the cap 25 is a channel 30 which normally rests against the upper end of the bowl 21, and clamped in said channel is a flat, metal screen 31 overlying the cage. In practice, the screen may be bowed into cone-shape, when its peripheral margin is engaged in the channel 30, or the channel may be formed about said margin of the

screen. The manner of assembly is unimportant. Above the channel 30, the wall of the cap is provided with an offset 32 supporting a flat, top plate 33 which is provided centrally with an opening 34.

The offset 32 and plate 33 of the cap 25 are both apertured throughout to permit a free flow of air therethrough, and formed in said offset is an opening 34'. Thus, a lighted match may be inserted through the opening 34' until the flame emerges at the opening 34 when, by drawing on the pipe, tobacco in the cage or, as shall presently appear, tobacco in the barrel employed, or a cigarette in the barrel, may be lighted without opening the cap, the mesh of the screen 31 being large enough for the purpose.

Removably engaged in the seat 15 of the base 10 is a foraminous barrel of woven wire or other approved material, the barrel being indicated as a whole at 35. As seen in detail in Figure 8 of the drawings, this barrel is formed of complementary, semi-cylindrical sections 36, and connecting the sections is a longitudinal hinge rod 37, the barrel being provided at its ends with sectional metallic reinforcing bands 38, the bands of which are soldered to the bowed wire sections of the cage. Mounting the hinge rod 37 is a bottom plate 39 having a duct 40 therethrough, and surrounding said duct is a nipple 41 adapted to frictionally fit in the sleeve 17 of the base 10 for connecting the barrel with the base. Projecting from the plate 39 is a lug 42 to which the hinge rod 37 is fixed so that the lower ends of the sections 36 may close about the plate, and associated with the reinforcing bands 38 are spring catches 43 for holding the sections closed. Projecting from the reinforcing band at the upper end of the barrel are diametrically disposed studs 44.

Associated with the barrel 35 is a wrapper holder, indicated as a whole at 45. As best seen in Figure 6 of the drawings, this holder includes a split, spring collar 46 which is channel-shaped in cross section, and formed in the outer flange of the collar, at diametric points, are bayonet slots 47. Suitably fixed to the inner flange of the collar is a number of depending spring fingers 48 spaced around the collar. As best brought out in Figure 3, the collar 46 is adapted to removably fit over the upper end of the barrel 35 so that the studs 44 may engage in the slots 47 for locking the wrapper holder in position when the spring fingers 48 will be adjacent to the wall of the barrel at the inner side thereof.

As will now be seen, the cage 23, barrel 35 and wrapper holder 45 may be removed when the bowl 21 may be filled with tobacco and the pipe used in the usual manner. If preferred, only the barrel 35 and wrapper holder 45 may be removed when the cage 23 may be filled with tobacco and smoke drawn therefrom through the pipe stem. For a still shorter smoke, only the wrapper holder 45 may be removed when the barrel 35 may be filled with tobacco and smoke drawn therefrom through the pipe stem. When the cage 23 and barrel 35 are both employed, the cap 25 will prevent the escape of sparks not only from the cage but also from the barrel.

To provide a cigarette, a suitable paper 49 is wound about the fingers 48 of the wrapper holder 45 in the manner suggested in Figure 7 of the drawings. This paper may be a conventional cigarette paper or, if preferred, some special medicated or flavored paper of like size and is wound about the fingers 48 to form a cylindrical wrapper 50 sealed in the usual manner by licking

one end of the paper. The sections 36 of the barrel 35 are then swung open. The wrapper holder 45 with the cylindrical wrapper 50 thereon is then installed between the sections, after which the sections are closed. The wrapper holder is then moved downwardly into place. Thus, as seen in Figure 4, the wrapper 50 will be clamped between the fingers 48 of the wrapper holder and the bands 38 of the barrel while the lower margin of said wrapper will be clamped between the periphery of the plate 39 and the barrel. The wrapper may then be filled with tobacco to form a cigarette 51.

For the purpose of smoking the cigarette 51, the bowl 21 is preferably removed, as seen in Figure 4, when the base 10 and stem 29 will provide a holder for the cigarette, the cage 23 functioning as a guard for the barrel 35. However, if preferred, the cage 23 with the cap 25 may also be removed when, as shown in Figure 5, the base will likewise function as a holder for the cigarette.

Having thus described my invention, what I claim is:

1. A tobacco pipe including a base having concentric seats and provided with a stem communicating with said seats through the innermost thereof, a bowl removably engaged in the outermost of said seats, a cage removably engaged in the intermediate seat between the innermost and outermost seats, a barrel removably engaged in the innermost seat, the cage and barrel being selectively useable to receive tobacco in lieu of the bowl, spring tongues surrounding the outermost seat to engage the bowl, and spring tongues surrounding the intermediate seat to engage the cage.

2. A tobacco pipe including a base having a stem, a removable bowl carried by the base, and a removable barrel carried by the base to communicate with the stem and formed of mating hinged sections, said barrel being useable in lieu of the bowl to receive tobacco and including a bottom plate having a nipple frictionally engaged with the base, and a fixed hinge rod carried by said plate and mounting said sections.

3. In a tobacco pipe, a base having a stem, an upstanding barrel carried by the base to communicate with the stem, and a removable holder having a collar to fit the upper end of the barrel and provided with fingers to extend within the barrel, said fingers being adapted to support a wrapper to receive tobacco disposed in said wrapper to provide a cigarette contained by the barrel.
